(57) **CLAIM**

The ornamental design for a dimpled exercise ball, as shown and described.

DESCRIPTION

FIG. 1 is a three-dimensional view, generally from the top, of a dimpled exercise ball of the invention; FIG. 2 is a three-dimensional view, generally from the bottom, of the dimpled exercise ball of FIG. 1; FIG. 3 is a front view of the dimpled exercise ball of FIG. 1; FIG. 4 is a rear view of the dimpled exercise ball of FIG. 1; FIG. 5 is a left side view of the dimpled exercise ball of FIG. 1; FIG. 6 is a right side view of the dimpled exercise ball of FIG. 1; FIG. 7 is a top view of the dimpled exercise ball of FIG. 1; and, FIG. 8 is a bottom view of the dimpled exercise ball of FIG. 1. The broken lines illustrate environmental elements of a dimpled exercise ball which form no part of the claimed design.
